ELECTRIC SNAP SWITCH

Filed May 5, 1928

UNITED STATES PATENT OFFICE

JOHN H. NELSON, OF CHICAGO, ILLINOIS, ASSIGNOR TO HARRY A. DOUGLAS, OF BRONSON, MICHIGAN

ELECTRIC SNAP SWITCH

Application filed May 5, 1928. Serial No. 275,352.

My invention relates to electric snap switches and resides in the provision of improved operating mechanism therefor whereby such a switch may be quickly placed in one and preferably in each circuit adjusting position.

The snap switch operating mechanism of my invention includes an expandible and contractible resilient member and an abutment against which one end of said member presses, one of the mutually engaging surfaces of said two elements being extended and along which the other member may slide, the element having said surface being adjustable to cause its said surface to be obtuse to the line of pressure of said resilient member to enable quick expansion of said member and to occupy an alternative position to effect another adjustment of said member, whereby the switch may be snapped into at least one of its circuit controlling adjustments. In the preferred embodiment of the invention, said abutment is provided with the extended surface, the abutment, as a whole, being adjustable to change the direction of the surface as described. This abutment is desirably so adjustable as to cause its said surface to be obtuse to the line of pressure of the resilient member upon opposite sides of said resilient member so that the switch may not only be snapped open but may also be snapped closed.

The invention will be more fully explained in connection with the accompanying drawings in which Fig. 1 is a longitudinal sectional view of the preferred embodiment of the invention showing the switch in a circuit closing adjustment, some parts appearing in elevation; Fig. 2 is a sectional view on line 2—2 of Fig. 1; Fig. 3 is a sectional view on line 3—3 of Fig. 1; Fig. 4 is a view somewhat similar to Fig. 1 but omitting some of the parts and showing more parts in elevation and also indicating the switch in circuit opening adjustment; Fig. 5 is a diagrammatic view illustrating the principle upon which the switch operates; and Fig. 6 is a sectional view on line 6—6 of Fig. 1.

The switch structure illustrated includes a cup-shaped metallic casing member 1

whose end wall engages the body portion 2 of a mounting plate 3 and has an annular shoulder 4 which is confined between the body portion 2 of the plate 3 and the flange 5 upon the hollow cylindrical extension 6 of the plate. A disc of insulation 7 closes the cup, this disc being held against the rim of the cup by means of clips 8 which enter recesses in the disc and are clinched over the disc. Two metallic current conducting contact posts 9 and 10 are disposed within the casing, these posts being mounted upon the insulating disc 7 and being provided with binding screws 11 and 12 upon the exterior side of the disc 7 for securing the circuit wires 13 and 14 in mechanical and electrical connection with said contact posts 9 and 10. Said posts are adapted to be simultaneously engaged by a metallic bridging plate 15 whereby the circuit containing said posts may be closed. This bridging plate is secured by means of a stirrup or strap 16 in firm mechanical assembly with a spring barrel 17 that is made of insulating material. Said bridging plate is secured against the cylindrical side of said spring barrel 17 and has an angular extension which laps the closed end of said spring barrel and terminates in a fulcrum end 18 which is received within a recess 19 that is formed upon the inner face of the disc 7, such disc thus constituting an abutment upon which the member 15 has a substantially fixed fulcrum, though the invention is not to be limited to such a fulcrum.

The spring barrel 17 is lined by a metallic tubular member 20 which is formed with an inturned shoulder 21 at the end thereof which is remote from the closed end of said barrel. A plunger 22 has a reduced portion which is surrounded by the shoulder 21 and has a base portion which is within the barrel lining 20, this base portion being sufficiently large to prevent the total discharge of the plunger 22 from said barrel. A coiled spring 23 is located within the spring barrel 17 and its lining 20, this coiled spring pressing, at its right hand end, against the closed end of the barrel 17 and, at its left hand end, against the plunger 22. The

structure which is inclusive of the parts 15, 16, 17, 18, 20, 21 and 22 constitutes an expandable and contractible resilient member having one abutment in the form of the disc 7.

5 The outer end of the plunger 22 is received within the wide slot 24 which is formed within the hub 25 of the handle 26, this hub constituting one of the abutments 10 of the device of my invention. The base of the slot 24 has an extended abutment surface 27 which is diagrammatically illustrated in Fig. 5. The handle has two shaft portion 28 by which it is journaled in the mounting 15 portion. As illustrated most clearly in Fig. 3, the handle may readily be turned upon the axis furnished by the shaft portions 28 merely by pressure exerted by a finger or thumb. The axis of turning movement for 20 the handle which is furnished by the shaft portions 28 and the handle 26 is between the flat surface 27 and the abutment at 18. The extent to which the handle may be turned is limited by the engagement thereof 25 with the outer or base portion of the cylindrical mounting portion 6. The straight line including the axis of the shaft portions 28 and the fulcrum axis at 18, 19 is midway between the two alternative lines of pressure 30 of the aforesaid resilient member which are effective when the handle is in its uppermost position and lowermost position and in each of which positions the surface 27 is oblique to said line of pressure. To bring 35 the aforesaid expandable member from either alternative position to the other, the abutment 25 is positively swung upon its axis by the operator until the axis or line of pressure of the spring 23 is shifted sufficiently to the other side of the line joining 40 the fulcra at 28 and 18, from the side previously occupied by this line of pressure, to cause the outer end of plunger 22 to quickly slide along the abutment surface 45 27 to bring the switch into its alternative adjustment. As illustrated, the switch is not only snapped open to avoid arcing, but is also snapped closed, though the invention is not to be thus limited. It will be observed 50 that the pivotal axis or fulcrum of the abutment 25 is between the abutment surface 27 and the fulcrum at 18, 19, whereby the switch contacts are maintained in firm engagement during the transition from circuit closing condition to the snapping circuit opening operation. While the fulcra at 25 and 18 are desirably in substantially fixed relation to each other and the circuit changing adjustments are effected by the 55 60 expandable and contractible resilient member which has been described, the invention is not to be thus restricted.

From the foregoing it will be observed that the extended abutment surface 27 is so 65 shaped as to escape turning engagement

with the contractible resilient member when the adjustable abutment is being moved to remove its extended abutment surface from one obtuse direction and partially toward the other obtuse direction whereupon the 70 resilient contractible member expands and turns, to snap the adjustable abutment throughout the balance of its movement.

Changes may be made without departing 75 from my invention.

Having thus described my invention, I 75 claim:

Operating mechanism for an electric snap switch including an expandable and contractible resilient member and two abutments between which said member is disposed, one of said abutments having an extended abutment surface along which the engaging end of said contractible member may slide, this abutment being adjustable 80 to cause its said surface to be obtuse to the line of pressure of said resilient member and in two directions alternately upon opposite sides of said line of pressure, the expandable and contractible member being fulcrumed on the other abutment, said extended abutment surface being shaped to escape turning engagement with said contractible resilient member when the adjustable abutment is being moved to remove the 85 extended abutment surface from one obtuse direction and partially toward the other obtuse direction whereupon the resilient contractible member expands and turns to snap the adjustable abutment throughout 90 the balance of its movement.

In witness whereof, I hereunto subscribe my name.

JOHN H. NELSON.
